CLAIM

The ornamental design for a bottle, as shown and described.

DESCRIPTION

FIG. 1 is a perspective view of a bottle showing my new design;

FIG. 2 is another perspective view of the bottle from FIG. 1; FIG. 3 is another perspective view taken from underneath the bottle from FIG. 1;

FIG. 4 is a front elevation view of the bottle from FIG. 1, the rear elevation being a mirrored view thereof;

FIG. 5 is a side view of the bottle from FIG. 1, the opposite side being a mirrored view thereof;

FIG. 6 is a top plan view of the bottle from FIG. 1; and, FIG. 7 is a bottom plan view of the bottle from FIG. 1. The broken lines show portions of the bottle that form no part of the claimed design.
